UNITED STATES PATENT OFFICE

JOHN TATTER AND WILLIAM H. PASCOE, OF CHICAGO, ILLINOIS

PISTON

Application filed November 30, 1925. Serial No. 72,360.

This invention relates to pistons and particularly to composite pistons for use in internal combustion engines.

Composite pistons have heretofore been employed more or less in internal combustion engines to overcome the faults which tend to obtain when the pistons are formed entirely of either cast iron or aluminum, the term "aluminum" being used 10 in this instance to include alloys comprising a relatively large proportion of that metal. A piston formed entirely of cast iron is relatively heavy and the inertia thereof during the operation of the engine decreases the efficiency of the engine. Aluminum pistons are relatively light but the greater co-efficient of thermal expansion of aluminum makes it necessary to allow excessive clearance between the piston and the cylinder wall, which 20 clearance detracts from the efficiency of the engine.

Our invention has among its other objects, the production of an improved composite piston which is convenient, durable and satisfactory for use wherever found applicable.

Another object of the invention is to provide a composite piston which may be manufactured at a relatively low cost.

Still another object of the invention is to 30 provide a relatively light piston which does not require much clearance between it and its cylinder wall.

Many other objects and advantages of the construction herein shown and described will 35 be obvious to those skilled in the art from the disclosure herein given.

To this end our invention consists in the novel construction, arrangement and combination of parts herein shown and described, 40 and more particularly pointed out in the claims.

In the drawing, wherein like reference characters indicate like or corresponding parts:

45 Fig. 1 is a central section through a piston embodying our invention;

Fig. 2 is a section taken on the line 2—2 of Fig. 1;

50 Fig. 3 is a section taken on the line 3—3 of Fig. 1; and

Fig. 4 is a fragmentary section through a piston embodying another form of the invention.

In Figs. 1, 2 and 3 of the drawing, we have shown a piston embodying one form of the invention and adapted to be used in an internal combustion engine or the like. The improved piston preferably comprises a body portion 10 formed from aluminum, but it is to be understood that we are limited to the use of aluminum only to the extent indicated in the appended claims.

Embedded in the body portion 10 is a helical member 11 formed of cast iron. The member 11 preferably comprises a plurality of spaced turns 12, which, in this instance, are substantially rectangular in cross section. Formed in the helical member 11 are undercut grooves 14 into which the metal of the body portion 10 projects.

The improved piston is preferably formed by casting the body portion 10 in a suitable mold, or the equivalent, the helical member 11 being suitably positioned in the mold before the aluminum is poured therein. Obviously, the fused aluminum will flow into the grooves 14 and prevent subsequent displacement of the turns 12 relative to the body portion 10.

In one embodiment of the invention, the outer diameter of the helical member 11 is substantially equal to that of the body portion 10, but less clearance is allowed between the piston and the cylinder wall (not shown) than is customary in the manufacture of aluminum pistons.

During the operation of an internal combustion engine, which includes our improved pistons, the helical member 11 of each piston tends to prevent the normal increase or decrease of diameter of the body portion 10 as the temperature within the engine rises, it being understood that the co-efficient of thermal expansion of aluminum is greater than that of cast iron and that aluminum expands with a greater rapidity than cast iron. However, the helical member 11 does not materially retard longitudinal expansion or contraction of the body portion 10 as the helical member functions as a spring.

The body portion 10 may be provided with annular grooves 16 adapted to accommodate the customary piston rings (not shown). A plurality of lugs 18 may be cast integral with the body portion 10 to hold a plurality of threaded studs 19, whereby bearing blocks 20 may be secured within the body portion. As shown, each bearing block 20 is provided with a plurality of drilled holes 22 adapted 10 to accommodate the studs 19 and is held firmly seated on the lugs 18 by nuts 24, or the equivalent, screw-threaded upon the studs 19. A wrist pin 25 may be mounted in the bearing blocks 20 to provide means whereby 15 the piston may be operatively connected to a piston rod, which is indicated at 26. If desired, the wrist pin 25 may be provided with a renewable sleeve 27.

In Fig. 4, we have illustrated another form 20 of the invention embodied in a piston comprising a body portion 10* with two helical members 11* embedded therein, turns of each of the members being disposed between turns of the other member. It will be noted that 25 the outer diameter of the body portion 10* is less than that of the helical members 11*, which, in practice, may be made of diameters allowing substantially the same clearance that is allowed in the manufacture of cast 30 iron pistons. In some embodiments of the invention, the pistons will have less than the usual clearance.

Having thus described our invention, it is obvious that various immaterial modifications may be made in the same without departing from the spirit of our invention; hence we do not wish to be understood as limiting ourselves to the exact form, construction, arrangement and combination of 40 parts herein shown and described or uses mentioned.

What we claim as new and desire to secure by Letters Patent is:

1. A piston having a helical member of 45 at least one complete turn embedded therein and secured thereto by tongue and groove construction.

2. A piston comprising a cylindrical body portion and a plurality of helical members 50 embedded in said body portion so snugly as to form substantially a unitary part thereof, turns of each of said members being disposed between turns of the other member.

3. A piston comprising a cast cylindrical wall, and a cast helical insert embedded in 55 said wall, the inner and outer surfaces of said insert forming a part of the corresponding surfaces of said cylindrical wall.

60 4. A piston comprising a cast cylindrical wall, and a cast helical insert embedded in said wall and forming portions of the inner and outer surfaces thereof, said insert comprising a plurality of turns.

65 5. A piston comprising a cast cylindrical

wall having spaced helical turns, and a helical insert disposed between said turns.

6. A piston comprising a cast cylindrical wall, and a cast insert arranged in a helical slot extending through the wall.

7. A piston comprising a cast cylindrical wall, and a plurality of cast helical inserts embedded in said wall, to form portions of the outer surface thereof, turns of each of said inserts being disposed between turns of the other insert. 75

8. A piston comprising a body portion, and a helical insert embedded in said body portion and forming a part of the inner and outer surfaces thereof. 80

9. A piston comprising a body portion, and a helical insert embedded in said body portion, said insert being substantially H-shaped in cross section, and the legs of said H forming part of the inner and outer surfaces of 85 said body portion.

10. A piston comprising a cast cylindrical wall and a cast helical insert embedded in said wall, said insert being substantially H-shaped in cross section and the legs of said H forming part of the inner and outer surfaces of 90 said wall, said insert comprising a plurality of turns. 95

In testimony whereof, we have hereunto signed our names.

JOHN TATTER.
WILLIAM H. PASCOE.

CERTIFICATE OF CORRECTION.

Patent No. 1,781,037.

Granted November 11, 1930, to

JOHN TATTER ET AL.

It is hereby certified that error appears in the printed specification of the above numbered patent requiring correction as follows: Page 2, line 67, claim 5, for the word "disposed" read cast; and that the said Letters Patent should be read with this correction that the same may conform to the record of the case in the Patent Office.

Signed and sealed this 20th day of January, A. D. 1931.

M. J. Moore,
Acting Commissioner of Patents.
